BROODER HOUSE

Perry S. Martin, Harrisonburg, Va.

Application January 14, 1928, Serial No. 246,799
Renewed August 18, 1934

12 Claims. (Cl. 119—31)

The present invention relates to a brooder house and aims to provide a novel and improved building of this character constructed and arranged for obtaining in an easy and more efficient manner proper air circulation and ventilation of the brooding room during various weather conditions and seasons of the year.

Another object of the invention is to provide a brooder house having a brooding room with an air passageway under the floor thereof in communication with the brooding room at opposite sides thereof, and a heating element at one point of communication of said passageway with the brooding room for setting up circulation through the brooding room and passageway.

A further object of the invention is the provision of a brooder house having openings in the floor thereof beneath windows and adjacent fresh air opening in the forward wall, and an air passageway under the floor communicating with said above mentioned openings and leading to the rear of the brooder house and in communication with other openings provided in the floor so that air passing through all of said openings will enter the brooding room at the rear thereof and around the heating elements of brooders prior to coming in contact with chicks, said openings in the forward portion of the floor receiving air cooled by passing downwardly from the windows and thus eliminate to a great extent said cold air passing over the floor to the heated hovers of the brooders.

A still further object of the invention is to provide a brooder house with a lined roof of the shed type sloping to the rear of the house, said roof having openings in the lining communicating with the brooding room of the house at the front and rear thereof, said openings being controlled by dampers, the space between the roof and lining forming an air passageway which communicates with the atmosphere at the forward side of the house, and a cool air damper-controlled opening at the rear of the house for admitting fresh air to said air passageway, said openings and dampers permitting the escape of foul air from the brooding room as well as circulating air between the lining and roof for aiding in cooling the brooding room.

It is also an object of the invention to provide a brooder house of the above indicated character which will be easy to construct, durable and efficient in use, and one especially suited for raising broilers or ten week old pullets.

With the foregoing and other objects in view, which will be apparent as the description pro-

ceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a vertical cross section through my improved brooding house,

Figure 2 is a fragmentary front elevation, showing portions of the structure in section,

Figure 3 is a fragmentary horizontal section taken on line 3—3 of Figure 2,

Figure 4 is a fragmentary section of a portion of Figure 1 showing the manner of controlling circulation, and

Figure 5 is a similar view showing a different adjustment for controlling circulation.

Referring to the drawings of my improved brooding house, it is to be noted that I have illustrated at the rear of a brooding room a brooder of the type covered by my Patent No. 1,592,377 issued July 13, 1926 and entitled Colony brooder, and my pending application entitled Colony brooder, filed January 21, 1927, and bearing Serial No. 162527, the brooder being designated by the numeral 10.

In carrying out the invention, the numeral 11 indicates a concrete base wall which extends around the building and longitudinally through the center thereof. Resting upon the concrete base wall 11 are the ends of joists 12, which support a floor 13. Extending upwardly from the concrete base wall 11 are studdings 14, which carry the siding 15 and lining 16 of some suitable sheet insulating material, for forming the walls of the brooder house. On the upper ends of the studdings arranged in a horizontal manner are sills 17 upon which the rafters 18 of the roof construction rest. The rafters are arranged at an angle and slope towards the rear of the building and have their ends extending beyond the front and rear walls so as to provide eaves, as indicated by the numerals 19 and 20 respectively. On the upper edges of the rafters 18 are arranged planks having any approved type of roofing material thereon, as indicated by the numeral 21, while on the under edges of the rafters is arranged material 22 similar to the material used for lining the walls of the building. Arranged longitudinally in the center of the building are studdings 23 which have their lower ends resting upon the longitudinal central portion of the cement base wall and carry

50
55

on their upper ends sills on which the intermediate portions of the rafters 18 rest. From the foregoing it can be seen that all walls, the roof, and the floor are provided with air spaces there-
in so as to provide an insulated construction.

In the center of the front wall of each brooding room is arranged a window frame 25, which supports a pair of sliding sashes 26 and 27 that may be opened for ventilation. While I have shown one brooding room and portions of the brooding rooms adjacent thereto in the brooder house, it is to be understood that the house can be of any desired length for containing any number of brooding rooms. The brooding rooms are divided from one another by providing partition planking 28 which stand upon their edges on the floor and extend from the front wall to the dividing partitions 29 of the hovers. Wire screening or the like may extend from the upper edges of the planking 28 to the ceiling if desired in order to positively prevent chicks from changing from one brooder room to another after the same are of sufficient size to fly over the planking 28. In the construction shown in the drawings, one window frame is arranged for each brooding room and is in the front wall thereof in the center thereof. If runs are provided on the front of the building, the chicks may gain access to said runs through the openings 30 arranged in the front wall at the sides of the windows, as clearly illustrated in Figure 2 of the drawings.

At the front of the building extending the entire length thereof through each brooding room is an elevated walkway 31, which rests upon the forward end of the planking 28 forming the partitions between the various brooding rooms. By this arrangement the chicks in the brooding rooms may pass under the elevated walkway and through the openings 30 when going to and from a yarding arranged in front of the building. The walkway 31 is of a slat construction as clearly illustrated in Figure 3 of the drawings. At the inner edge of the elevated walkway 31 are arranged corner posts 32 for the brooding rooms and gate posts 33 to which the wire screening or netting is attached. Between the gate posts 33 gates 34 are arranged so that the attendant walking down the walkway may gain access to the brooding rooms. Supported by the rafters 18 above the elevated walkway 31 is a track 35 upon which a carrier may run for carrying litter from the various brooding rooms or may be used for carrying feed or straw to said rooms.

At each window at the lower portion and beneath same is arranged a box-like structure 36 forming an air duct which extends down through the floor 13 and has its lower end in communication with the air passageway under the floor, while its upper end is in communication with the interior of the brooder house. At the lower end of the box-like structures 36 wire mesh or screen 37 is provided for preventing litter, or the like, dropping through the box-like structures and closing the passageways under the floor. Each box-like structure 36 has a rear wall 38 which is spaced from the window and end walls 39 which extend from the rear wall 28 to the siding 15 on the forward wall. By this arrangement, it can be seen that cool air in the forward portion of the brooder house may pass downwardly through the box-like structure 36 into the passageway beneath the flooring. In the siding 15 beneath the windows are arranged openings 40 which have wire mesh material 41 thereacross so as to permit fresh air to enter into the lower portion of

the air duct 36. At each end of the openings 40 are arranged spacing blocks 42 which have attached to their outer faces shield boards 43 for preventing a direct draft through the openings 40, as clearly illustrated in Figure 1 of the drawings. In order to control the entrance of fresh air through the openings 40, dampers 44 are hinged at their upper edges, as at 45, to the lower cross member of the window frame 25. On the front joists 12 are arranged strips 46, against which the dampers 44 may be swung to engage so as to close off all entrance of air from the outside of the building, while on the end members 39 of the box-like structures forming air ducts 36 are arranged cleats 47 which limit inward swinging movement of the dampers so as to prevent the closing of communication from the interior of the brooder house to the passageways under the flooring. Attached to the dampers 44 are small chains 48, or the like, which may be engaged by hooks 49 for holding the dampers 44 in adjusted positions, said hooks being carried by the rear wall 38 of the box-like structures.

By referring to Figure 1 of the drawings, it can be seen that the joists 12 extending from the front wall to the rear wall of the building will form sufficient space at the intermediate portion of the building for permitting air to pass to the rear of the building, the passage of air being indicated by arrows. In the floor 13 at the rear of the building are provided openings 50 which are covered by wire mesh material 51 through which the air passing from the forward end of the building enters the brooding rooms. Over the openings 50 are arranged the brooders such as those previously referred to so that the air entering will pass around the heating elements of the brooders and be heated prior to coming in contact with chicks on the floor 13. The passage of air through the brooders is also indicated by arrows. It will be noted that the back wall of the hover is spaced slightly from the wall 16 whereby a small amount of air enters the room without passing through the brooder. This feature, however, is not claimed in the present application.

In the lining 22 of the roof construction at the forward end thereof is a plurality of openings 52, one being arranged in the forward portion of each brooding room, while in the lining of the roof construction adjacent the rear wall are provided openings 53, one being arranged in each brooding room. The openings 52 and 53 are adapted to be opened and closed by dampers 54 and 55 respectively. By opening and closing the dampers 54 and 55, different room temperatures can be had, as said openings 52 and 53 communicate with the air passageway 56 between the roof and lining. At the eave 20 of the roof construction exteriorly of the building are provided openings 57 which are opened and closed by hinged dampers 58, said dampers being held in adjusted positions by means of chains 59. It can be seen that when the dampers 58 are opened air may pass between the lining and roof construction and thus aid in cooling the brooding rooms. The forward edge of the roof construction is constructed so that the passageway 56 opens to the atmosphere.

At the forward edge of the roof construction where the passageway 56 communicates with the atmosphere a ventilator structure 60 is provided which extends the entire length of the building. On the ends of the rafters 18 are attached upright supporting members 61 which carry on their upper ends a longitudinal strip of sheet

metal bent intermediate its side edges similar to a hip roof construction, as indicated by the numeral 62, while attached to the forward ends of the rafters and the outer sides of the uprights 61 is another longitudinal strip of sheet material as indicated by the numeral 63. This strip of sheet material has its upper edge slightly turned outwardly, as at 64, while its lower edge is turned inwardly, as at 65. On the inner sides of the uprights 61 is another longitudinal sheet metal member 66 having its upper edge turned outwardly, as at 67, and its lower edge also turned outwardly, as at 68, engages under a portion of the roofing material. By this arrangement air from the passageway 56 may escape through the ventilator structure and rain and wind are prevented from entering the ventilator and passing down the passageway 56. While I have shown this type of ventilator, it is to be understood that any approved type may be used.

As shown in Figure 1 of the drawings, the various dampers are arranged in positions for operation of the brooder house during mild weather. By having the damper 44 in the brooder room illustrated slightly open, fresh air is permitted to mix with the air passing down in rear of the window 25 and pass under the floor to the rear of the building where said air passes around the heating elements of the brooder when entering the brooding room. The arrows indicate the direction of air circulation. As the air passes from under the hovers, the same due to being heated will rise and pass through the rooms. When the air reaches the forward wall of the room and is in rear of the window, the same is naturally cooled, and the cool air will pass downwardly along the window and enter the air duct 36 so as to pass under the floor and again pass around the heating elements of the brooder.

During warm weather the dampers 54, 55 and 58 are opened and cool air entering the openings 57 will pass between the lining 22 and roof 21 to the forward portion of the building, while a portion thereof will enter the brooding rooms through the openings 53, as indicated by arrows. As the air passes between the lining and roofing of the building, the same will naturally carry the heat penetrating the roof out through the ventilator to the atmosphere. As the damper 54 is also open, it can be seen that hot air in the forward portion of the building where the ceiling is highest cannot bank and all hot air will be permitted to also escape through the ventilator. By closing the dampers 58 and 55 at the rear of the house so that the openings 57 and 53 are closed and the opening 52 remains open, it can be seen that air may exhaust through the opening 52 to the atmosphere, thus retaining a higher temperature in the brooding room than when all dampers are open, due to the fact that cool air is not permitted to circulate through the roof construction and into the rear of the room. To increase the temperature to a higher degree the dampers 58 and 54 are closed and the damper 55 opened so the only escape hot air has from the brooding rooms is through the opening 53. When the dampers are in this position hot air will bank or be pocketed in the upper forward portion of the room due to the inclination of the ceiling which will cause the temperature in the room to rise to a higher degree. It can thus be seen that by adjusting the positions of the various dampers different brooding room temperatures can be made.

The object of having the openings in the for-

ward portion of the floor of the brooding house and openings in the rear portion of the floor of the brooding house is to prevent the cold air which comes in contact with the windows from passing back over the floor to the brooders and coming in contact with the chicks on the floor, and for producing a circulation for eliminating dead air spaces and thus completely ventilating the brooding rooms.

Having thus described my invention, what I claim as new is:

1. A brooder house comprising a roof, a floor, side and end walls, a plurality of brooding rooms arranged in said brooder house, a brooder arranged in each brooding room, one of said side walls having openings therein for permitting chicks to pass to and from said brooding rooms, windows arranged in said side wall having said openings therein, and an elevated walkway arranged adjacent said windows and extending across all of said brooding rooms.

2. A brooder house comprising a roof, a floor, side and end walls, a plurality of brooding rooms arranged in said brooder house, a brooder arranged in each brooding room, heating elements in each brooder, one of said side walls having openings therein for permitting chicks to pass to and from said brooding rooms, windows arranged in said side wall having said openings therein, an elevated walkway arranged adjacent said windows and extending across all of said brooding rooms, box-like structures arranged adjacent said windows and between the openings in said side wall, said box-like structures communicating with the interior of the brooder house, there being air passageways arranged under the floor of said brooder house and communicating with said box-like structures, said floor having openings therein communicating with the air passageways and adjacent the heating elements of the brooders.

3. A brooder house comprising a roof, a floor, side and end walls, a plurality of brooding rooms arranged in said brooder house, a brooder arranged in each brooding room, heating elements in each brooder, one of said side walls having openings therein for permitting chicks to pass to and from said brooding rooms, windows arranged in said side wall having said openings therein, an elevated walkway arranged adjacent said windows and extending across all of said brooding rooms, box-like structures arranged adjacent said windows and between the openings in said side wall, said box-like structures communicating with the interior of the brooder house, there being air passageways arranged under the floor of said brooder house and communicating with said box-like structures, said floor having openings therein communicating with the air passageways and adjacent the heating elements of the brooders, and there being other openings arranged in the side wall having said first mentioned openings and windows therein communicating with said box-like structures for permitting fresh air to enter said box-like structures.

4. A brooder house comprising a roof, a floor, side and end walls, a plurality of brooding rooms arranged in said brooder house, a brooder arranged in each brooding room, heating elements in each brooder, one of said side walls having openings therein for permitting chicks to pass to and from said brooding rooms, windows arranged in said side wall having said openings therein, an elevated walkway arranged adjacent said windows and extending across all of said brooding rooms, box-like structures arranged adjacent said

- windows and between the openings in said side from the passageway to the room thru the brooder, said floor having a second opening below said wall opening, a conduit against said wall for conducting fresh air from said wall opening into the passageway thru said second opening, said conduit having an open top whereby currents of cold air passing down said wall will enter the conduit and thus be prevented from sweeping across the floor, and a damper for controlling the amount of fresh air passing thru said wall opening. 5
10. The device of claim 8 in which a window is provided in said wall directly above the open top of said conduit. 10
11. The brooder house of claim 8 in which said wall opening is just above the floor level and a window is provided in said wall directly above said opening, said conduit consisting of a box-like structure rising from the floor to about the bottom of the window and the width of the open top of said conduit being approximately equal to that of the window whereby substantially all of the cold air passing down the inner face of the window enters the conduit. 15
12. The brooder house of claim 8 in which said wall opening is just above the floor level and a window is provided in said wall directly above said opening, said conduit consisting of a box-like structure rising from the floor to about the bottom of the window and the width of the open top of said conduit being approximately equal to that of the window whereby substantially all of the cold air passing down the inner face of the window enters the conduit. 20
13. A brooder house comprising a roof, a floor, side walls, and end walls for providing a brooding room, said brooding room having an air passageway under the floor and communicating therewith adjacent opposite side walls thereof; and a brooder arranged with a heating element thereof at one point of communication of the passageway with the brooding room, said roof having an air passageway therein communicating with the atmosphere at opposite sides of the house and communicating with the brooding room adjacent opposite side walls of the house. 25
14. A brooder house comprising a roof, a floor, side walls, and end walls for providing a brooding room, said brooding room having an air passageway under the floor and communicating therewith adjacent opposite side walls thereof; a brooder arranged with a heating element thereof at one point of communication of the passageway with the brooding room, said roof having an air passageway therein communicating with the atmosphere at opposite sides of the house and communicating with the brooding room adjacent opposite side walls of the house, and means for controlling communication between the brooding room and the air passageway in the roof. 30
15. A brooder house comprising a brooding room having an air passageway arranged under the floor of the brooding room, said floor having openings therein at points on opposite sides of said room, said openings providing communication between the room and the passageway, a brooder adjacent one wall of the room and over one of the openings whereby air entering the room from said one opening passes through the brooder, an open top box-like structure against the side of the room opposite to that where the brooder is located, said structure surrounding the other opening, and means for admitting fresh air from outside the room into said structure and thence into said passageway. 35
16. A brooder house comprising a brooding room having an air passageway under the floor of the room, a brooder at one side of the room, the wall at the opposite side of the room having an opening therein to the atmosphere, said floor having an opening under said brooder for admitting air

PERRY S. MARTIN.
